Primary Examiner — Darlington Ly(74) *Attorney, Agent, or Firm* — Birch, Stewart, Kolasch & Birch, LLP(57) **CLAIM**

The ornamental design for a wireless headset, as shown and described.

DESCRIPTION

1. Wireless headset
1.1 is a front perspective view of a wireless headset showing our new design;
1.2 is a front elevation view thereof;
1.3 is a rear elevation view thereof;
1.4 is a left side elevation view thereof;
1.5 is a right side elevation view thereof;
1.6 is a top plan view thereof;
1.7 is a bottom plan view thereof;
1.8 is a rear perspective view thereof;
1.9 is front perspective view thereof when folded; and
1.10 is a left side elevation view thereof when in use.
The broken line showing portions of the wireless headset and environmental user do not form part of the claimed design.

1 Claim, 10 Drawing Sheets(56)
